[57] **CLAIM**

The ornamental design for a splatter shield, as shown and described.

DESCRIPTION

FIG. 1 is a side, top perspective view of a splatter shield showing our new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken line showing of a splatter shield rim in FIGS. 1-7 is for illustrative purposes only and forms no part of the claimed design.
